INVENTOR
EDWARD W. ROBINSON
BY HIS ATTORNEY
Harry Smith

UNITED STATES PATENT OFFICE.

EDWARD WILLIAM ROBINSON, OF SAVANNAH, GEORGIA.

RETAINER FOR TERMINAL STAVES OF WIRE-BOUND BARRELS.

1,291,154.

Specification of Letters Patent.

Patented Jan. 14, 1919.

Application filed November 24, 1917. Serial No. 203,718.

To all whom it may concern:

Be it known that I, EDWARD W. ROBINSON, a citizen of the United States, residing in Savannah, Georgia, have invented certain 5 Improvements in Retainers for Terminal Staves of Wire-Bound Barrels, of which the following is a specification.

My invention relates to that method of manufacturing wire bound barrels in which 10 a set of staves is first confined between inner and outer binding wires crossed or twisted between the successive staves of the set and in which the terminal staves of the set are then jammed together and held in 15 such close relation, my invention consisting of a simple and effective device for effecting such retention of the terminal staves.

In the accompanying drawings

Figure 1 is a perspective view of a stave 20 retainer constructed in accordance with my invention;

Fig. 2 is a transverse section through portions of the terminal staves with the retainer in place thereon;

25 Fig. 3 is a face view of the staves and retainer shown in Fig. 2, and

Fig. 4 is a transverse section on the line 4—4, Fig. 3.

All of the views are on an enlarged scale.

30 In Figs. 2 and 3 of the drawing 1, 1, represent the terminal staves of the set, 2 the binding wires, and 3 the twisted ends of said binding wires, beyond the terminal staves. When the terminal staves are 35 jammed together these twisted portions of the wires are embedded in the edges of the staves, as shown in Fig. 2, but in order to maintain the set of staves in barrel form it is necessary to retain said terminal staves

40 in such abutting relation to one another, and, with this object in view, my improved retainer consists of a metallic sheet or plate comprising opposite flat edge members 5—5, for bearing against the outer faces of the 45 terminal staves on opposite sides of the outer binding wires, these edge members being connected by an arched central member 6 which bridges said outer wires, as shown in Fig. 4.

50 At each end of each of the side members

5 of the retainer is an inwardly projecting pointed tooth 7, and, when the retainer is driven into place on the outside of the terminal staves 1, these teeth penetrate the staves, as shown in Fig. 2.

55

The teeth 7 are considerably longer than the thickness of the stave, and when the retainer is being applied to the staves the latter are supported upon a suitable anvil which contacts with the points of the teeth 60 7 when the latter pass through the staves and thus causes the teeth to turn outwardly so as to bite into the inner faces of the staves 1, as also shown in Fig. 2.

Not only does the retainer thus serve to 65 firmly hold the terminal staves in their proper abutting relation but said retainer is so firmly secured to the staves that loosening or displacement of the same is likewise effectually prevented.

70

The side members 5 of the retainer are not in line with one another laterally, hence the teeth 7 at each end of the retainer are in different transverse planes and the risk of splitting the stave when said teeth are 75 driven into the same is thereby reduced to a minimum.

I claim:

The combination of the terminal staves and inner and outer wires of a wire-bound 80 barrel, the terminal ends of said wires being united to each other between the terminal staves, and a retainer comprising an arched central member for bridging the outer binding wires, and opposite flat edge members, 85 one on each side of said arched central member for bearing against the outer face of the terminal staves, each of said members being of a length sufficient to overlap the terminal staves on the opposite sides of the 90 joint between them, and the end portions of the edge members being tapered to a point and bent down at a right angle so as to form pointed teeth in different lateral planes from the central arched member of the 95 retainer, which teeth are driven into the terminal staves.

In testimony whereof, I have signed my name to this specification.

EDWARD WILLIAM ROBINSON.
